(57) CLAIM

The ornamental design for a women's boot, as shown and described.

DESCRIPTION

FIG. 1 is a front, top perspective view of a women's boot, showing my new design;

FIG. 2 is a rear, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures are for the purposes of illustrating portions of the women's boot that form no part of the claimed design.

The short-short-long dashed broken lines immediately adjacent to the claim area in the figures are for the purposes of illustrating the boundaries of the women's boot, and form no part of the claimed design.
